(Model.)

L. D. BENNER.

Paper Bag.

No. 242,499.

Patented June 7, 1881.

UNITED STATES PATENT OFFICE.

LORENZO D. BENNER, OF GALESBURG, ASSIGNOR TO LUCIUS G. FISHER, JR.,
OF CHICAGO, ILLINOIS.

PAPER BAG.

SPECIFICATION forming part of Letters Patent No. 242,499, dated June 7, 1881.

Application filed March 18, 1881. (Model.)

To all whom it may concern:

Be it known that I, LORENZO D. BENNER, of Galesburg, in the county of Knox and State of Illinois, have invented a new and Improved 5 Bag or Sack; and I do hereby declare the following to be a full, clear, and exact description of the same, reference being had to the accompanying drawings, forming part of the specification.

10 My invention is a "square-bottom" bag in which the side portions are of uniform thickness throughout. The bottom is closed by seams, which securely seal the same without being unduly thick at any point, and are so 15 arranged that the bag will readily open and assume its form in the act of filling.

In the drawings, Figure 1 is a view illustrating the form of sheet from which a bag can be made; Fig. 2, a view showing the shape 20 of the edge of the sheet when formed into a tube and flattened; Fig. 3, a view showing the form of the edge when the tube is opened; Figs. 4 to 6, views illustrating the bag at different stages of the manufacture; Figs. 7 and 25 8, views showing the completed bag folded; Fig. 9, a perspective view showing the completed bag inverted and opened.

The bag may be made from a sheet or from 30 a continuous tube, and the steps in the manufacture may be performed wholly or in part by machinery, and may be varied without altering the essential features of the product.

I do not here describe the machinery nor claim any special process, as these will form 35 the subjects of separate applications for Letters Patent; and for the purposes of this application I shall describe the bags as made from sheets.

The form to which each sheet is cut is shown 40 in Fig. 1, which is substantially an oblong or square blank, but cut to form at one edge (which will be at the bottom of the bag) two tongues or lips, B B, so situated that when the edges of the sheet are pasted together these 45 tongues will be at the edges of the bag, as shown in Figs. 2 and 3. The sheet may also be cut so as to leave a tongue, A, at one side, projecting beyond the edge y of the other side, as shown in Figs. 1, 2, and 4.

50 In the process of manufacturing the bag the

side portions are brought to such a position that the central point, s, of each tongue B will be on a line with the body of the bag, as shown in Figs. 4 and 5, in which the side portions are flattened, so that the transverse form of 55 the folded sheet or tube corresponds to that of the letter H, Fig. 5. It should be understood, however, that this mode of folding is not essential, it only being necessary to bring the point s in line with the body. The lip A 60 is then folded down and pasted, as in Fig. 6.

One or both sides, tt, of the folded portion is then bent over on a diagonal line, w, as shown in Figs. 4 and 6, and this portion is pasted down to the side t and to the body of the bag, 65 where it overlies the same. The other side is then folded in like manner, or both sides may be folded down simultaneously. In any case the tip or end of the tongue B will be folded over, across, and close the edge of the 70 body portion as far as it projects over the same, as shown in Fig. 6, thereby effectually sealing the bag at this point.

It is apparent that where the tongues are 75 long enough the folded lips may extend from each edge to the center of the bag, thereby closing the end without necessarily using the tongue A.

After the lips are thus folded and pasted down the bag will be complete, and the sides 80 may be folded into the bellows shape shown in Fig. 8, or otherwise. However folded, the mere act of filling the bag will cause its bottom to assume the shape shown in Fig. 9.

The seams of the bag thus constructed are 85 not of undue thickness. They are arranged so as to add to the strength of and effectually and securely close the bag, especially at the corners, and are of a character to be formed without the necessity of folding in the bag to a 90 bellows shape during the process of manufacture, or of making it on a former; nor is it necessary to open the bag after folding over the end, or to tuck in the corners after pasting and securing the seams. The folding down 95 and pasting of the corners, in effect, completes the bag in form ready for use, and when the bag is made from a continuous tube, and the tongues B are wide enough to meet at the center, this folding and pasting down of the cor- 100

ners constitutes the entire process of making the bag.

As the side folds, *q*, extend from the mouth to the bottom through only a single thickness of material, the bag assumes its shape in folding and filling more readily than when the seam terminates at a portion of the bag adjacent to the bottom of two or more thicknesses.

I claim—

10. 1. A square-bottom bag in which prolongations of the side portions are folded down and secured to the bottom, and in which the sides consist each of one thickness of paper throughout, substantially as set forth.

2. A paper bag consisting of a sheet of paper formed into a tube, with projecting side tongues folded down upon and transversely crossing the bottom, substantially as set forth.

3. The combination, with the body and side portions formed and folded as set forth, of a ²⁰ lip, *A*, constituting an extension of one side of the body folded over and secured to the other side, substantially as set forth.

LORENZO D. BENNER.
